SHEET METAL RADIATOR

Francis M. Lambert, Narberth, Pa., assignor to
Heintz Manufacturing Company, a corporation
of Pennsylvania

Application February 4, 1931, Serial No. 513,257

1 Claim. (Cl. 257—124)

The present invention relates to heat exchange apparatus and particularly to sheet metal radiators, and an object of the invention is to provide an improved radiator of this character which has 5 its primary heating surface, or what is sometimes known as the radiator body or tube, made of a steel alloy of high surface stability, so as to resist rust and other corrosion and thus have a more permanent character and longer useful 10 life, and which at the same time has a high degree of thermal efficiency as compared with sheet metal radiators heretofore employed.

Such steel alloys of high surface stability are 15 commonly called "stainless steel" and for convenience will be so designated herein, although it is to be understood that the term as here used does not refer to the quality of stainlessness, strictly speaking, since discoloration is not of importance in connection with the present invention, but refers to the characteristic of having 20 corrosive-resistant surfaces.

While the use of "stainless steel" for making the primary heating surfaces of sheet metal radiators is of great advantage because of its corrosive-resistant property, there is, on the other 25 hand, a difficulty in the way of its use owing to the fact that it has a lower thermal conductivity than the ordinary steel usually employed for the purpose, and hence its use is apparently less desirable from the standpoint of thermal efficiency. 30

I have discovered that this problem can be overcome by making the primary surface of the radiator of "stainless steel" which is relatively thin, and suitably securing to the primary surface a plurality of diathermic fins of a different metal having a higher thermal conductivity than the "stainless steel". 35

By making the walls of "stainless steel" relatively thin, the rate of heat transfer transversely 40 therethrough is increased so as to maintain an efficient and satisfactory heat output notwithstanding the relatively low thermal conductivity of the "stainless steel". To this end the thickness of the "stainless steel" used, is reduced, preferably as much as practicable consistent with the range of pressures, or differences in pressures 45 against its inner and outer surfaces, which the primary surface of the radiator must be able to withstand according to the character of heating system with which it is to be employed. Such relatively thin walls can not be safely used where the primary surface is of ordinary sheet steel or like corrosive metal, since they become weakened under the corrosive action of the heating medium, 50 and hence when such corrosive metals are em-

ployed the walls must be thicker than would otherwise be necessary, in order to afford a margin of safety, but even then the continued corrosive action weakens them as time goes on and thus limits the useful life of the radiator. However, with my invention the use of relatively thin walls is rendered possible owing to the corrosive-resistant quality of the "stainless steel", and in spite of the reduced thickness of the walls the radiator has both a safe and permanent character. 5 The use of relatively thin walls also permits a saving of metal. 10

By suitably securing the diathermic fins to the primary surface, the relatively thin walls of the latter are reinforced and at the same time the 15 heat transferred through such walls is given off rapidly to the air. The latter function would not be satisfactorily performed if the fins were made of "stainless steel" since the relatively low conductivity of that metal would prevent the 20 heat from traveling rapidly in the planes of the respective fins and hence the fins would not operate efficiently to transfer the heat to the air. But by making the fins of a different metal having a higher thermal conductivity than "stainless steel" I overcome this difficulty and secure 25 the efficient emission to the air of the heat transferred through the "stainless steel" walls of the primary heating surface. 30

The various features of novelty which characterize my invention are pointed out with particularity in the claims annexed to and forming a part of this specification. For a better understanding of the invention, however, and the advantages possessed by it, reference should be 35 had to the following descriptive matter and the accompanying drawings, in which I have described and have illustrated certain embodiments of my invention. 40

In the drawings—

Fig. 1 is a side elevation, partly broken away and partly in section, of one form of sheet metal radiator embodying my invention. 45

Fig. 2 is a top plan view thereof, partly broken away and partly in section. 50

Fig. 3 is an end elevation thereof, partly broken away and partly in section. 55

Fig. 4 is a transverse section on the line 4—4 of Figure 2, parts being broken away and the cap being removed. 60

Fig. 5 is a transverse section, partly broken away, showing the two companion sections of the radiator body spaced apart, the sections being equipped with fins and ready to be assembled. 65

Fig. 6 is a fragmentary side elevation, partly 70

broken away, of another form of sheet metal radiator embodying my invention.

Fig. 7 is an end elevation thereof, with the pipe coupled to the radiator shown in section.

Fig. 8 is a transverse section, partly broken away, on the line 8—8 of Figure 6.

Fig. 9 is an end view, showing this form of the invention in its open position, ready for final assembly.

Fig. 10 is a detailed sectional view, showing the use of rivet projection welding for securing the fins.

In the embodiment of my invention shown in Figs. 1 to 5, inclusive, the primary heating surface or body of my improved sheet metal radiator is made in two, separate, companion, vertical sections or halves 1 and 2 which are formed from relatively thin sheets of "stainless steel". As above pointed out the "stainless steel" used is preferably as thin as practicable consistent with the range of pressures, or difference in pressures against its inner and outer surfaces, which the primary heating surface must be able to withstand according to the heating system with which the radiator is to be employed. Under ordinary conditions I find that 18 or 20 gauge sheet "stainless steel" is suitable for the purpose of the present invention.

Each section is substantially pan-shaped and is provided along its upper and lower edges with outstanding flanges 3 adapted to abut against the corresponding flanges of the other section when the sections are later assembled. The pan-shaped form of the sections is employed where it is desired to have the primary surface in the form of a flattened tube vertically elongated in cross-section, and has the advantage of providing broad, flat, vertical faces on each side of the primary surface.

The sections are formed at both ends with semi-cylindrical portions or members 4 extending vertically entirely thereacross and provided along their free or outer side edges with outstanding flanges 5. The corresponding portions 4 are adapted to match with their flanges 5 in abutting relation when the sections 1 and 2 are assembled, whereby to provide a tubular inlet and a tubular outlet at the opposite ends of the primary surface or radiator body.

After the two sections have been thus formed and before they are united, each section has a series of vertically disposed fins 6 secured to and projecting perpendicularly from the outer face of its side wall. These fins are made of any suitable sheet metal having a higher conductivity than "stainless steel", as for instance, ordinary steel or aluminum. The fins on each section are spaced apart at suitable longitudinal intervals, and extend across the broad, flat outer face of the section in extended thermal contact therewith. In this embodiment of the invention, the fins are shown as U-shaped in cross-section with the base of the U secured to the side wall of the corresponding section.

The fins are rigidly and permanently secured to the sections and held at all times in firm and even contact therewith, so as to serve the dual function of reinforcing the broad, flat side walls of thin "stainless steel" to increase their rigidity and ability to withstand pressure differences, and of giving off rapidly to the air the heat transferred through such thin "stainless steel" walls.

In order to secure the fins effectively to the companion sections homogeneous joints produced by electric welding are employed. When there is

no marked difference in the coefficients of expansion of the "stainless steel" forming the primary surface or radiator body and of the different metal forming the fins, spot welding, roller seam welding or projection welding is employed according as found most suitable. On the other hand, when there is a marked difference in such coefficients of expansion, rivet projection welding is employed, in which instance a rivet 7 is inserted through an opening 8 in the fin and welded to the outer face of the "stainless steel" body section, as shown in Fig. 10. The opening 8 is of slightly larger diameter than the rivet 7 in order to permit sufficient play to take up the difference in expansion between the body sections and the fins. The rivet is preferably of the same material as the radiator body to avoid producing in the area of the weld a different alloy which might not be corrosive-resistant, and then too if a different metal were used for the rivet the weld might be porous or non-homogeneous and permit the heating medium to work out into the rivet and corrode it to such an extent that it might come loose or the heating medium eat through.

All of these methods of welding require access to and operation from both the inner and outer faces of the radiator body, particularly where the latter is made of relatively thin sheet metal, since it is necessary that a support be provided on the inner face to prevent deformation of the thin wall under pressure exerted by the outer electrode. This support may be afforded by the inner electrode, or a separate support may be provided and the inner electrode attached to the metal of the radiator body according to the practice known as indirect welding. The problem of thus affording access to and operation from both faces of the radiator body is solved in the present invention by making the same in two companion sections or halves and welding a series of fins to each section before the sections are assembled.

After the companion sections have been equipped with the fins they are then assembled in matching relation and the abutting flanges 3 and 5 thereof electrically welded together as by roller seam welding or any other suitable welding process, to provide homogeneous fluid-tight joints. Interiorly screw-threaded bushings 9 are inserted in the open ends of the tubular inlet and outlet in the opposite ends of the radiator and welded in place, to complete the radiator. The bushings are made of the same material as the radiator body so as to avoid the possibility of setting up electrolytic action under the influence of the heating medium, as would be likely to occur if the radiator embodied different metals, both exposed to the heating medium.

When thus assembled, the radiator is complete and ready for installation, except that where fins of regular steel are employed, it is preferably dipped or sprayed or otherwise given an exterior coating of paint or other suitable material. In installing the radiator the pipe connections 10 for the supply and return for the heating medium, such as hot water or steam, are fitted, respectively, to one of the bushings 9 of the inlet and one of the bushings 9 of the outlet. In such instance a closure plug 11 is applied to one of the remaining bushings 9 and a cap 12 provided with an air valve 13 may be secured to the other. The radiator may, of course, be installed not only as a single unit but in other suitable ways. For instance, two or more units may be installed in superimposed relation, with connections between 75

the lower bushings of the upper unit and the upper bushings of the lower unit.

In the embodiment of the invention shown in Figs. 6 to 9, inclusive, the companion sections 1^a and 2^a are formed from a single sheet of relatively thin "stainless steel" bent upon itself or folded so that the sections are joined along one edge, preferably the upper edge as indicated at 14, and are initially spread apart from such edge, 10 as shown in Fig. 9. In this position access is afforded to the inner faces of the sections, thus permitting operation from both the inner and outer faces thereof to secure the series of fins 6 to the outer faces by means of electric welding as 15 above described. In this embodiment the semi-cylindrical portions or members 4^a extend longitudinally of the sections for a suitable distance from the ends thereof, and are adapted to match, upon the assembling of the sections, to provide 20 a tubular inlet and a tubular outlet which open outwardly in a horizontal direction at the opposite ends of the radiator. The interior screw-threaded bushings 9^a which are secured 25 within the open ends of the inlet and the outlet to receive the pipes 10, may be, and preferably are, welded to one of each pair of corresponding semi-cylindrical portions 4^a while the companion sections are in their open position. Upon the 30 subsequent assembling or closing together of the companion sections, the outstanding flanges 3 along their lower edges and outstanding flanges 5^a at their ends are brought into abutting relation and electrically welded together, and the bushings 9^a are welded to the remaining semi-cylindrical portion 4^a of each corresponding pair. At 35 one or both ends of the radiator body semi-cylindrical members 15 are formed in the meeting ends of the sections 1^a and 2^a, preferably adja-

cent the joined edge 14 thereof, and co-act in the assembled position to provide a nipple within which an interiorly screw-threaded bushing 7^a is welded and is adapted to receive an air-valve or like device (not shown). Except as above pointed out, the construction and method of producing this embodiment of my invention is the same as in the embodiment first referred to. 5

While my improvement is particularly adapted for use in making a "stainless steel" radiator according to the present invention, it is to be understood that it is not limited to the production of such radiators but may be employed in making sheet metal radiators of other materials. It is also to be understood that the form of the companion sections of the radiator body and also of the inlet and outlet thereof may be varied as desired in different instances; that fins of angular form in cross-section or any other suitable shape may be employed and that various other changes 10 15 20 25 30 35 may be made without departing from the spirit and scope of the invention as defined in the appended claim.

Having thus described my invention, I claim and desire to protect by Letters Patent of the 25 United States:

A sheet metal radiator comprising a radiator body or primary heating surface, and fins secured thereto and both reinforcing the walls of the radiator body and giving off heat transferred therethrough rapidly to the air, the body and the fins being formed of different sheet metals and the metal of the fins having a higher thermal conductivity than that of the body, and the fins being secured to the body by rivets of the same 30 35 metal as and welded to the body.

FRANCIS M. LAMBERT.
